UNITED STATES PATENT OFFICE.

WILLIAM J. CARROLL, OF WEST HAVEN, CONNECTICUT, ASSIGNOR TO SARGENT & COMPANY, OF NEW HAVEN, CONNECTICUT.

LOCK.

Application filed November 7, 1921. Serial No. 513,401.

To all whom it may concern:

Be it known that I, WILLIAM J. CARROLL, a citizen of the United States, residing in West Haven, county of New Haven, State 5 of Connecticut, have invented certain new and useful Improvements in Locks, of which the following is a full, clear, and exact description.

This invention relates to locks and, more 10 particularly, to a lock adapted to be applied to the door of a public building and designed for use in connection with a so-called panic bar which normally lies across the inner face of the door in such a manner 15 that persons crowding against the same will automatically release the latch and allow the door to swing open. However, while my improvements may be particularly adapted, generally speaking, for a lock of 20 this type, it will be understood that certain features of my invention are broadly novel and are applicable and useful in locks or latches of almost any type.

Ordinary locks of this character have been 25 so constructed that when the panic bar is depressed or pushed toward the door, the bolt is slidably retracted within the lock case and the door is then free to swing open. However, experience has shown that when 30 a number of persons under the stress of exciting circumstances crowd against the door and press the same outwardly, the friction between the latch or lock bolt and the strike plate becomes so great as to prevent the 35 withdrawal of the bolt, and hence the opening of the door is impossible.

The present invention has for its object, therefore, the overcoming of the disadvantages above referred to and the provision 40 of a lock or latch so constructed that the bolt will be allowed to disengage itself from the strike plate without having to overcome a frictional force due to pressure against the door in an opening direction.

45 Another object of my invention is to provide a lock with a bolt mounted to swing away from the strike plate when the bolt is released and when an opening pressure is applied to the door.

50 A still further object of my invention is to provide a lock with a bolt which may be

retracted within the lock case both by a sliding and by a pivotal movement or by a combination of the two.

More specifically, my invention has for its 55 object the provision of a lock with a bolt of such a character and so mounted in the lock case that while it will be normally held against retraction by contact with the strike plate when the door is moved in an opening direction, the bolt may be released by pressure upon the latch or panic bar, and the bolt permitted to be retracted within the lock case by such contact with the strike plate.

Further, my improved lock is provided 60 with a bolt which is adapted to be retracted by contact with the strike plate under certain conditions, both upon closing and upon opening movements of the door.

To these and other ends, the invention 65 consists in the novel features and combination of parts to be hereinafter described and claimed.

In the accompanying drawings: 75

Fig. 1 is an edge elevational view of a portion of a door provided with my improved lock;

Fig. 2 is a side elevational view of the 80 parts shown in Fig. 1;

Fig. 3 is a side elevational view of the lock, the cover having been removed;

Fig. 4 is a sectional view on line 4—4 of 85 Fig. 3;

Fig. 5 is a front elevational view of the lock similar to Fig. 3, but showing the dog controlling plunger retracted within the lock case in its normal position when the door is closed;

Fig. 6 is a sectional view on line 6—6 of 90 Fig. 5;

Fig. 7 is a fragmentary front elevational view of the parts of the lock in the position assumed by them when the dogging slide is locked in inoperative position; 95

Fig. 8 is a sectional view on line 8—8 of Fig. 5;

Fig. 9 is a view similar to Fig. 8, but showing the latch bolt in different positions as it is retracted by the strike plate; 100

Fig. 10 is a sectional view on line 10—10 of Fig. 3;

Fig. 11 is a perspective view of the dogging slide; and

Fig. 12 is a top plan view of the locking slide and tumbler.

- 5 In order to illustrate the principles of my invention, I have shown at 10 a door supplied with a lock of the type known as a mortise lock having a case 11 and a face plate 12 designed to lie substantially 10 flush with the edge of the door and having openings 13 and 14 through which project a dog controlling plunger 15 and a bolt head 16. While at the present time it is common to use a mortise lock, it will be 15 understood that the principles and novel features of my invention are applicable to rim locks and locks of other types which it is unnecessary to illustrate or enumerate.
- I have shown upon the inside of the door 20 an escutcheon plate 17 provided with an opening for a cylinder lock of any desired or usual type 18, and having lugs 19 to which is hinged a so-called panic bar 20 operable to permit the opening of the door.
- 25 This escutcheon plate 17 is adapted to be held in proper position relative to the lock case 11 by means of bolts or screws 21 passing through lugs 22 formed on the upper part of the lock case, so that a finger 23 upon 30 the panic bar may always lie in proper position to engage certain mechanism within the lock case to permit the operation of the bolt. It will of course be apparent that any other operating means may be used equally 35 as well as a panic bar, and such other operating means may consist of an ordinary thumb latch or knob. Upon the inside of the door is applied an escutcheon plate 24, also provided with an opening through 40 which a cylinder lock 25 of any usual type may project.

Movably mounted within the lock case 11 is a bolt of novel and improved structure and supported in the lock case in a novel 45 manner. This bolt, as shown, might be termed a latch bolt in that the bolt head 16 has a bevelled face 27 considered in connection with the face plate of the lock case, and a second face 28 projecting substantially 50 normally from the face plate or substantially parallel with the surface of the door. To this bolt head is pivotally connected at 26^a a stem 29 which passes between a pair of guiding lugs 30 which may be formed upon the lock case. A spiral spring 31 reacts between a collar 32 fixed upon the forward portion of the stem and a collar 33 loosely mounted upon this stem adjacent the guiding lugs 30 to normally urge the bolt to its 55 protracted position shown in Figs. 3, 5 and 8. At its rear end the stem 29 is provided with a crosshead 34 by which the movement of the stem and bolt is controlled. It may be stated that, as illustrated in the

drawings, the door upon which the lock is 65 mounted is adapted to open to the outside and therefore the bevelled face 27 of the bolt head is so arranged as to face the inside of the door or so that the bolt will be slidably retracted against the tension of the 70 spring 31 when the door is closed by the engagement of its bevelled face with a strike plate of the usual form (not shown) in the door frame.

The bolt head 16 is mounted for both 75 pivotal and sliding movement to retracted position within the case. To accomplish this end, the bolt is provided with a pair of trunnions 35 which are mounted in slots 36 formed upon the lock case, these slots being 80 open at their rear ends to permit the bolt head to be slidably retracted to the dotted line position shown in Fig. 8. The bolt head 16 can, of course, also be moved pivotally about the trunnions 35 into the partially retracted dotted line position shown in Fig. 9. In order to permit such pivotal movement of the bolt head about the trunnions 35 and relative to the stem 29 and to 85 permit its retraction within the case by a sliding motion, the case is slightly enlarged at its forward portion as plainly shown at 90 37 and 38 in Figs. 8 and 9. The case, of course, may be enlarged so as to be of proper width throughout, but I prefer to arrange the bolt in what may be termed a well, or 95 the like, to accommodate the large bolt head.

In order to control the retraction of the bolt, I provide a dogging slide 40 arranged in the lower part of the lock case as clearly 100 shown in Figs. 5, 6 and 7, and this slide is provided with a web 41 which passes at the side of and above the stem 29 and terminates in an arm 42 provided with a slot 43 which is adapted to receive the crosshead 34 upon the end of the stem when the slide is in depressed position. It will be apparent that when this crosshead is received in the slot 43, as shown in Fig. 5, the retraction of the bolt 16 by either pivotal or sliding movement is prevented, as the stem 29 is dogged against movement and the head 16 cannot move while the stem is held fast.

The slide 40 is adapted to be guided in its movement in the lock case by a pair of guides 44 formed upon the case between which a broadened end 45 of the slide is adapted to fit. This end 45 of the slide projects into a recess 46 formed in the lock case and in which operates the finger 23 upon the panic bar. Thus this finger 23 is permitted to contact with the slide and to move it upwardly from its dogging to its inoperative position. A shoulder 47 is provided upon one side of the slide to limit its downward movement by contact with a lug formed in the lock case, and in order to normally urge the slide to its depressed or dogging 115 120 125

position a spring 48 is provided which acts against the lower shoulder of a recess 49 in one side of the slide. The slide is also provided with a horizontally projecting finger 50 which will be again referred to hereafter.

It will of course be obvious that when the door is in open position, it will be desirable to have the dogging slide 40 raised to inoperative position in order that when the door is closed, the bolt may be retracted within the case by contact of its bevelled surface 27 with the strike, and then after the door is closed spring out into a properly formed opening in the strike plate in the usual way. For this purpose a dog controlling plunger is provided, consisting of a plunger head 15 pivotally mounted within the lock case by the trunnions 15^a and 15^b, and a stem 51 pivotally connected thereto at 52 and normally urged to outward or protracted position by a spring 53 reacting against a collar 54 fixed upon the stem 51 and a collar 55 loosely mounted upon this stem and disposed adjacent a pair of guiding lugs 56 through which the stem is adapted to slide. This stem 51 is provided with a crosshead 57 and pivotally mounted within the case at 58 is a dog controlling bell crank lever having one end 59 resting against this crosshead and having its other end 60 disposed below the horizontally projecting finger 50 upon the dogging slide.

It may sometimes be desirable to prevent the movement of the dogging slide to operative position when the door is closed or to raise it from operative position from the outside of the door by means of a key. As shown in Fig. 1, there is no other means provided for opening the door from the outside except a suitable key through the agency of the cylinder lock 25. For this purpose a sliding lock bar 61 is reciprocally mounted within the lock case and provided with talons 62 adapted to be engaged by the rollback 63 mounted upon and rotated by the cylinder lock 25. Upon the pin 64 on the lock bar 61 is pivotally mounted a tumbler 65 having a portion 66 adapted to extend between the talons 62 to be engaged by the rollback 63 and having lugs 67 and 68 adapted to cooperate with notches 69 and 70 formed in a portion of the lock case to hold the locking bar in a predetermined position. The tumbler is normally urged to operative position by a spring 71. The bar 61 is provided with a horizontally extending finger 72 adapted to abut the arm 59 of the bell crank lever when the locking bar is moved to the left, as shown in Fig. 7, to either prevent the dogging slide from being moved to its dogging position or to positively move this slide from this position to its inoperative position if the lock bar is moved by the key after the door is closed.

The operation of my device is as follows. When the door is in open position, the parts normally stand in the position shown in Fig. 3. It will be apparent that as in the particular embodiment of my invention shown, there is no means to positively retract the latch bolt 16, the door is closed by merely being moved toward the door frame. The bevelled face of the plunger 15 and the bevelled face 27 of the bolt 16 face in the same direction so that these bolts are both retracted by contact with the strike plate when the door is closed. The bolt 16 in this instance will be slidably retracted to its dotted line position, as shown in Fig. 8, and pivotal movement about the trunnions 35 in the direction which would result from contact with the outer edge of the strike plate will be prevented by the lock case. Immediately the door is in closed position, the bolt 16 will spring out, urged by the spring 31 to enter an opening in the strike plate. The controlling plunger 15, however, will normally face a closed or solid portion of the strike plate and will be held retracted within the case as shown in Fig. 5. In this position the dogging slide 40 will no longer be held elevated by the spring 53 through the agency of the crosshead 57 and dog controlling bell crank lever and will be depressed by the spring 48 into the position shown in full lines in Fig. 5 where the crosshead 34 is received in the slot 43. This will be the normal position of the parts when the door is closed. If it is desired to open the door from the inside, slight pressure is applied to the panic bar 20 or other operating means provided, and the dogging slide will be raised to its full line position shown in Fig. 7. The stem 29 will now be released, and if pressure in an opening direction is applied to the door, the bolt 16 will be, by contact with the strike plate, moved pivotally about the trunnions 35 to its partially retracted dotted line position shown in Fig. 9. This pivotal movement of the bolt will of course continue until a part thereof contacts with the stem 29 so as to prevent further relative pivotal movement of the bolt and stem. It will be apparent from Fig. 4 that the stem enters a recess 73 of substantial dimensions in the head so that a considerable relative movement is permitted before the shoulder 74 of this recess contacts with the stem. If desirable, a sufficient movement may here be permitted to retract the bolt to permit opening of the door. However, this is not necessary as when the bolt is moved to the partially retracted dotted line position shown in Fig. 8, the surface 28 becomes in effect a bevelled surface to contact with the side of the opening in the strike plate and further pressure upon the door will slidably retract

the bolt within the lock case to the position shown in full lines in Fig. 9. The bolt is now completely retracted and the door may be opened at will. It will be obvious that in 5 this manner it is unnecessary to overcome the friction between the surface 28 of the bolt and the side of the opening in the strike plate as an opening force applied to the door after the dogging slide has been lifted tends 10 to throw the bolt away from the strike plate and to retract it within the case instead of creating a frictional resistance to such retraction.

If when the door is closed and the parts 15 are in the position shown in Fig. 5, it is desired to gain access from the outside, it is only necessary to apply the proper key to the lock 18, and the rotation of the rollback will, by engagement with the tumbler 65 20 and talons 62, move the lock bar 61 to the left as shown in Fig. 7, the finger 72 engaging the arm 59 of the dogging controlling lever and raising the dogging slide to inoperative position as shown in Fig. 7 so that 25 the door may now be freely opened by a pull upon the same in an opening direction.

A second lock 18 may be provided upon the inside of the door and provided with a rollback 63' so that from either the inside 30 or the outside the dogging slide may be locked in its inoperative position so that the door may be freely opened at all times.

While I have shown and described a preferred embodiment of my invention and 35 have enumerated some of the advantages and uses thereof, it will be apparent that the novel features and principles disclosed will be capable of broad application and of many modifications and variations which 40 will fall within the spirit of the invention and within the scope of the appended claims.

What I claim is:

1. In combination, a lock case, a latch bolt 45 slidably mounted therein, said bolt also having a pivotal connection with the case, a stem connected to the bolt and slidably mounted in the case to control both the slideable and pivotal movements of the bolt.

2. In combination, a lock case, a latch bolt 50 slidably mounted therein, said bolt also having a pivotal connection with the case, a stem connected to the bolt and slidably mounted in the case to control both the slideable and pivotal movements of the bolt, and 55 means to dog said stem in position to hold the bolt protracted.

3. A lock case, a latch bolt slidably 60 mounted therein, said bolt also having a pivotal connection with the case, a stem slidably mounted within the case to control both pivotal and sliding movements of the bolt, said stem being connected to the bolt at a point eccentric to the pivotal connection of the bolt with the case.

4. In a door lock, a case, a slideway pro-

vided therein, a bolt slidably mounted in said way, said bolt also having a pivotal connection with the case, and a stem pivotally secured to the bolt and adapted to control the latter in both its pivotal and sliding movements. 70

5. In a door lock, a case, a slideway provided therein, a bolt slidably mounted in said way, said bolt also having a pivotal connection with the case, and a stem pivotally secured to the bolt and adapted to control the latter in both its pivotal and sliding movements, and means to dog said stem in position to prevent retraction of the bolt. 75

6. In a door lock, a case, a bolt pivotally 80 and slidably mounted in the case, a stem connected to the bolt to control the movement thereof, a slide to engage said stem to dog the latter against movement, a dog controlling plunger to control said slide, and additional manually operable means to control the slide. 85

7. In a door lock, a case, a bolt pivotally 90 and slidably mounted in the case, a stem connected to the bolt to control the movement thereof, a slide to engage said stem to dog the latter against movement, and key operated means to render said dog controlling plunger ineffective. 95

8. In a lock, a case, a bolt pivotally and 100 slidably mounted therein and adapted to swing pivotally toward a retracted position when a pushing force is applied to the door to open the same, means to retain the bolt in protracted position to hold the door closed, and manually operated means to release said holding means, a continued application of force to said manually operated means causing said bolt to be first swung about its pivot and then slidably retracted 105 into the lock case by the door strike. 110

9. In a lock, a case, and a bolt mounted 115 therein for both pivotal and bodily sliding movements, said bolt being retracted by contact with the door strike by a combined pivotal and sliding movement. 120

10. In a lock, a case, a bolt mounted therein, and adapted to be protracted from the case to engage a door strike and means causing the retraction of said bolt by the 115 strike by a combined pivotal and bodily sliding movement when the door is moved in an opening direction.

11. In a lock, a case, a bolt mounted therein for both pivotal and bodily sliding movement, and a single means to hold said bolt against either of said movements. 120

12. In a lock, a case, a bolt mounted therein for both pivotal and bodily sliding movement, a single means to hold said bolt against either of said movements, and means to render said holding means inoperative. 125

13. In a lock, a case, a bolt mounted therein for both pivotal and bodily sliding movement, and a single means rendered operative 130

- by the closing of the door to hold said bolt against either of said movements.
14. In a lock, a case, a bolt mounted therein for sliding movement when engaging the strike plate upon closing movement of the door, and for pivotal movement when engaging the strike plate upon an opening movement thereof, and means to dog said bolt against movement when the door is closed. 70
15. In a lock, a case, a bolt mounted therein for sliding movement when engaging the strike plate upon closing movement of the door, and for pivotal movement when engaging the strike plate upon an opening movement thereof, means to dog said bolt against movement when the door is closed, and means to lock said dogging means in inoperative position. 80
20. 16. In a lock, a case, and a bolt pivotally and slidably mounted therein, said mounting comprising cooperating pins and guide ways therefor on said bolt and case. 85
25. 17. In a lock, a case, and a bolt pivotally and slidably mounted therein, said mounting comprising pins on said bolt and guide slots formed on the case in which the pins are mounted. 90
30. 18. In a lock, a case, a bolt mounted therein for retraction by either pivotal or bodily sliding movements, a stem attached to the bolt and a spring surrounding the stem to normally urge said bolt to protracted position. 95
35. 19. In a lock, a case, a bolt mounted therein and adapted to be retracted by contact with the strike when the door is moved in an opening direction, and a dogging slide to dog said bolt in protracted position. 100
40. 20. In a lock, a case, a bolt mounted therein and adapted to be retracted by contact with the strike when the door is moved in an opening direction, a dogging slide to dog said bolt in protracted position and means to move said slide to inoperative position. 105
45. 21. In a lock, a case, a bolt mounted therein and adapted to be retracted by contact with the strike when the door is moved in an opening direction, a dogging slide to dog said bolt in protracted position and means extending without the casing to move said slide to inoperative position. 115
50. 22. In a lock, a case, a bolt mounted therein and adapted to be retracted by contact with the strike when the door is moved in opening direction, a dogging slide to dog said bolt in protracted position and key operated means to render said slide inoperative. 120
55. 23. In a lock, a case, a bolt mounted therein and adapted to be retracted by contact with the strike when the door is moved in an opening direction, a dogging slide to dog said bolt in protracted position, and means controlled by the opening and clos- 125
- ing of the door to move said slide into and out of operative position.
24. In a lock, a case, a bolt mounted therein and adapted to be retracted by contact with the strike when the door is moved in an opening direction, a dogging slide to dog said bolt in protracted position and a dog controlling plunger to control the position of said slide. 70
25. In a lock, a case, a bolt mounted therein and adapted to be retracted by contact with the strike when the door is moved in an opening direction, a dogging slide to dog said bolt in protracted position, a lever having a portion engaged with the slide, and a dog controlling plunger to control the position of the lever. 80
26. In a lock, a case, a bolt mounted therein and adapted to be retracted by contact with the strike when the door is moved in an opening direction, a dogging slide to dog said bolt in protracted position, a lever having a portion engaged with the slide, and a key operated bolt engaging said lever to render the slide inoperative. 85
27. A lock case, a bolt movably mounted therein, means for holding said bolt against retraction by the door strike when the door is moved in an opening direction, means to release said holding means and permit said bolt to be so retracted, and means to lock said holding means in inoperative position. 90
28. In a lock, a case, a bolt movably mounted therein, the bolt head having a bevelled face, and a back substantially normal to the edge of the case, and means for mounting said bolt in the case to permit it to swing so that the normal side of the bolt head becomes in effect a bevelled side to contact with a strike plate, and causes the bolt to be retracted slidably into the lock. 100
29. In a lock, a case, a bolt movably mounted therein, the bolt head having one side at an oblique angle to the edge surface of the door and another side substantially normal thereto, and means to permit the normal side to swing to a protracted position wherein it makes an oblique angle with the surface of the door, and cams the bolt slidably into the lock case. 110
30. In a lock, a case, a bolt pivotally and slidably mounted therein, said bolt having a beveled side to engage the strike plate to retract the bolt, and another side to engage the strike plate to hold the door closed, and means to cause the slideable retraction of the bolt by contact of the last named side with the plate. 115
31. In a lock, a case, a bolt mounted therein and adapted to be retracted by contact with the strike when the door is moved in an opening direction, a dogging slide to dog said bolt against retraction, a lever to control said slide, a dog controlling plunger 120
- 130

to control the lever, and a key operated member to actuate said lever to hold the slide in inoperative position regardless of the position of said plunger.

5 32. In a lock, a case, a bolt mounted therein adapted to be retracted by contact with the strike when the door is moved in an

opening direction, means to dog the bolt in protracted position, and key operated means to render said dogging means inoperative. 10

In witness whereof, I have hereunto set my hand on this 4th day of November, 1921.

WILLIAM J. CARROLL.
